LENGTH MEASUREMENT AND CONTROL
IN WEB PRINTING

Morris Sorkin, Bergenfield, and George J. Schowerer, West Englewood, N.J., assignors to Champlain Company, Inc., Roseland, N.J., a corporation of New York
Filed Jan. 19, 1961, Ser. No. 83,835
8 Claims. (Cl. 250—219)

This invention relates to repeat length measurement and control for a rapidly moving printed web.

Multicolor printing requires superposed printing of different colors in registration. The printing operation frequently is followed by a converting operation which may be simple rewinding or may be cutting, punching, and creasing as when forming a box blank. Mechanisms including electric eye scanners have been highly developed to secure registration. However, very little has been done in the way of precision measurement of the length of the deviation from desired length of the printed matter along the web.

Theoretically the print length equals the circumference of the print cylinder. However, the actual length may vary because of factors such as humidity, drying temperature, impression pressure, degree of wetting by the ink, web thickness, variations in the material of the web itself, and so on.

The general object of the present invention is to measure the repeat length of printed matter on a continuous web. The apparatus may terminate in an indicator which indicates deviation from a desired length, and such indication may be watched by an operator and used for manual control of mechanism intended to correct the deviation. If desired, the apparatus may terminate in a recorder having a movable pen which makes a continuous record of the repeat length or its deviation. This may be done when the printed web is rolled up for subsequent use, and only later is unrolled for feed into cutter-creaser mechanism to form a box blank. The written record of repeat length may be kept with the roll and later used as a guide by the operator when feeding that particular roll into the cutter-creaser.

In still another form the apparatus may provide automatic control or correction of deviation, with a view to maintaining a desired repeat length.

The repeat length is measured between accurately spaced electric scanners. Inasmuch as the repeat length being printed on a web by one printing cylinder may differ greatly from the repeat length being printed on a different web by a different diameter cylinder, a further object of the present invention is to make this possible without requiring physical movement of one scanner relative to the other. The disclosed apparatus will handle a wide range of repeat length, say from 20 inches to 50 inches, while using compact apparatus occupying only a small amount of floor space, and without requiring any relative movement of the scanners, which instead are rigidly mounted in position.

Another object is to select a desired electrical pulse from among many which may be transmitted by the scanner, so that the mark on the web used for measurement of repeat length need not be a special mark located in a "clear track", and instead may be a part of the regular printed matter.

Still another object is to provide improved electrical circuitry to help accomplish the foregoing objects. A still further object is to provide circuitry the operation of which is independent of changes in rotative speed of the printing cylinder or cutter-creaser.

To accomplish these objects and other more specific objects which will hereinafter appear, our invention resides in the apparatus elements and their relation one to

2

another, as are hereinafter more particularly described in the following specification. The specification is accompanied by drawings in which:

FIG. 1 is an elevation showing apparatus embodying features of the invention;

FIG. 2 is a schematic view drawn to much smaller scale, showing a press line including our invention;

FIG. 3 is a vertical section taken approximately in the plane of the line 3—3 of FIG. 1;

FIG. 4 represents a remotely controlled reversible motor and a part of its control circuit;

FIG. 5 is a block diagram explanatory of the invention;

FIG. 6 shows the relation between certain signals and scanner pulses used in the circuitry of FIG. 5;

FIG. 7 is a wiring diagram for the power supply;

FIG. 8 is a wiring diagram for each of the two scanners;

FIG. 9 is a wiring diagram for the phase micrometer; and

FIG. 10 is a wiring diagram for the computer which receives signals from the scanners of FIG. 8 and the phase micrometer of FIG. 9, and which controls an indicator or/and recorder or/and correction mechanism.

Referring to the drawing and more particularly to FIG. 2, a web 12 is fed from a web roll 14 by means of a power driven feeding unit 16. The web is supplied to a multicolor gravure press line which in this case comprises gravure press units with overhead dryers, indicated at 18, 20, 22, and 24. The web is then fed by a pull unit 26 to a roll 28. However, it could go directly to a cutter-creaser.

In accordance with the present invention, the repeat length is measured by apparatus shown at 30. This may be placed in any desired location, and in the present case is located between the first and second print units 18 and 20. A remote computer is shown at 90. The measurement may be shown on an indicator-recorder 31, which may be remotely located.

For automatic control of the repeat length we here show mechanism which varies the web tension. Specifically, the web is formed into a loop around a roll 32 located somewhat like a dancer roll, but in this case subject to force supplied by an air cylinder 34. The air pressure supplied to the cylinder 34 is controlled by a regulator valve 36, the adjustment of which is varied by a reversible remotely controlled motor 38. The apparatus 30 and more specifically the computer 90 controls the reversible motor 38, but such remote control may be applied to other means for varying repeat length. For example, the tension may be varied by mechanism shown in patent application No. 682,958 filed September 9, 1957, and entitled "Variable Web Tension for Uniform Layoff," since issued on March 20, 1962, as Patent No. 3,025,791, or the repeat length may be varied by changing compression of the web as in application Serial No. 688,034, filed October 3, 1957, and entitled "Multicolor Printing on a Continuous Web," since issued on February 21, 1961, as Patent No. 2,972,297, both filed by George N. Auerbacher.

In accordance with usual practise, the press units are all driven from a common line shaft 40. A registration means, not shown, usually of the planetary differential gear type, is provided between the line shaft and each press unit. The line shaft 40 also drives the feed rolls at 16 and the pull rolls at 26, but preferably through variable speed drives such as a Reeves or a PIV drive indicated at 42. For pulse selection, described later, the line shaft 40 also drives a phase micrometer indicated at 44.

The repeat length measurement unit indicated at 30 in FIG. 2 is shown in detail in FIGS. 1 and 3 of the drawing. Referring there, the web 12 passes over a

fixed roll 46, a movable roll 48, and another fixed roll 50, which together form a loop of web having parallel sides 52 and 54. A web scanner 56 is located at fixed roll 46, and a second web scanner 58 is located at the other fixed roll 50. The roll 48 is mounted for adjustment of its position along a plane bisecting the space between the sides 52 and 54 of the loop, thereby adjusting the length of the web between the scanners. In the present case the movable roll 48 may move between a bottom position shown at 48 and a top position shown at 48'. This provides a very wide range of adjustment, which in the specific machine here shown extends from twenty inches to fifty inches of repeat length.

A scale 60 and pointer 62 are relatively moved when the roll 48 is moved, and the scale 60 is preferably marked in terms of the repeat length between the scanners 56 and 58. The sides of the loop 52 and 54 are kept parallel so that the scale may be a uniform one.

The means for adjusting the position of the movable roll is best shown in FIG. 3, and comprises upright spaced screws 64 and 66 at the ends of the movable roll 48. The screws carry the bearings 68 and 70 of roll 48, and the two screws are geared together for simultaneous equal rotation.

More specifically, the upper end of screw 64 carries a mitre gear 72, and the upper end of screw 66 carries a similar mitre gear 74. These mesh with mitre gears 76 and 78, which are both carried on a horizontal shaft 80 which is rotatable by means of a crank 82. For compactness the mitre gears 76 and 78 may face in opposite direction, and therefore turn the screws 64 and 66 in opposite direction, in which case one has a right hand and the other a left hand thread.

If desired, the bearings 68 and 70 may be accurately guided by the sides of the frame, in addition to being carried by the screws, in which case the latter would serve primarily to change the height of the bearings. However, because the sides 52 and 54 of the loop of web are parallel, the bearings may be supported solely by the screws 64 and 66, there being no sideward force.

A block diagram for the circuitry is shown in FIG. 5 of the drawing. The web scanners are indicated at 56 and 58 located above the fixed rolls 46 and 50. The scanners include localized amplifiers, and the output is led to the computer, indicated by the large dotted rectangle 90. Additional amplification may be provided within the computer, indicated at 92 and 94. The web scanner comprises a light source lamp, condenser lens and filter, a viewing lens, aperture, photo tube, an amplifier, and a cathode follower.

In order to avoid the need for a "clear track" with a special mark on the web, by selecting a desired pulse from among many, a phase micrometer is employed. This consists of a shallow cup or cylinder 96 driven one-to-one with the printing cylinder (or knife, in the case of a cutter-creaser) by means of a shaft 98. This may be driven conveniently by a chain or gearing or timing belt from the line shaft. There is a light source lamp 100 inside the cylinder, and two photoelectric cells 102 and 104 outside the cylinder, together with appropriate lenses, etc., inside and outside the cylinder. This entire assembly is in a protective housing which is rotatively adjustable to establish any needed phase position. The cylinder has apertures or slots which are approximately, but not exactly, diametrically opposed, and which also are displaced axially. Thus there are two optical systems using a common light source lamp 100. One system supplies a live gate once per revolution which is fed through line 106 to a web pulse selector 108. The other provides a micrometer signal once per revolution which is fed through line 110 to a micrometer regulator 112. This has two like outputs supplied to cathode followers, indicated at 114 and 116.

The mechanical arrangement of the phase micrometer 96 (and of the scanners 56 and 58) need not be

10

described in greater detail, being substantially the same as those used in the model C-300 registration apparatus made by Champlain Company, Inc., of Roseland, New Jersey.

5 The timed relation between the live gate, the micrometer signal, and the scanner pulses is indicated in FIG. 6. The live gate 118 has a desired length, which in the present case is approximately ten degrees out of the full rotation of 360 degrees. This gate is shown rectangular in form, but it could vary at the forward and rear edges.

15 The selection of the correct scanner pulses from among others along the printed matter is accomplished by requiring coincidence with the live gate 118, as indicated at 148 in FIG. 5, by means of circuitry subsequently described. The pulse from one web scanner is shown at 120, and that from the other is shown in broken lines at 122. Actually the scanner pulses are used to trigger sharp "pick-off" pulses, and these are what is shown at 120 and 122. When the repeat length is correct, these pulses are simultaneous, but when there is a deviation they become separated, as shown.

20 The two micrometer signals provided at 114 and 116 in FIG. 5 are indicated by the solid and dotted lines at 124 in FIG. 6. The wave form has a sloping edge, and the potential of the micrometer signal at the instant of the pick-off pulse is indicated by a solid line at 126. This potential is a measure of the timing of the pick-off pulse triggered by a scanner pulse. The two micrometer signals in fact are truly coincident when the repeat length is correct, and are here slightly displaced only to show that there are two of them. In the case here shown the delay of pick-off pulse 122 is indicated by the height of the dotted line 128 relative to the reference solid line 126. Increased deviation increases the spacing, and a deviation in opposite sense (shortened instead of lengthened repeat length) would bring the dotted line 128 below the reference line 126.

25 Reverting now to FIG. 5, the micrometer regulator 112 gives the micrometer signal a desired wave shape and size and provides two equal and isolated outputs, which are supplied to the cathode followers 114 and 116 which then lead to pickoff circuits 144 and 146. It will be recalled that the live gate was supplied at 106 to the web pulse selector 108. The scanner pulse from amplifier 92 is combined with the live gate, and the scanner pulse from amplifier 94 also is combined with the live gate, with resulting wave form indicated at 148. This raises the selected pulse, relative to other pulses received outside the live gate, that is during almost all of the rotation of the printing cylinder. The subsequent circuitry, in this particular case a thyratron tube, requires the said increased voltage of the selected pulse, for firing.

30 It will be seen that one micrometer signal is combined with one selected pulse in pickoff circuit 144, while the other micrometer signal is combined with the other selected pulse in pickoff circuit 146. The outputs of the pickoff circuits are combined in a differential amplifier 150 which results in a signal which is positive-going for a deviation in one direction, negative-going for a deviation in an opposite direction, and the potential of which depends on the amount of deviation.

35 This may be used in any or all of three ways. One is in a meter which indicates deviation, and this is shown locally at M and remotely at 152. Another is to record the deviation on a moving sheet of paper, and this is shown at 154. In the present case a combined meter is used, that here shown being a typical commercially available instrument such as that made by the Esterline-Angus Company Inc., of Indianapolis, Indiana, but other such indicator-recorder meters may be used.

40 The output of the differential amplifier 150 also may be used in an automatic correction circuit 155, which typically has a three-wire output indicated at 156 to control a remote reversible motor. In the present case such

a motor is indicated at 38 in FIG. 2. One example of wiring for such a motor is schematically represented in FIG. 4 of the drawing. It will be understood that the motor control may be through relays, as indicated at 190 and 192 in FIG. 4, leading to the motor 38. Pilot lights may be provided, indicated at I1 and I2, which may differ in color, say green and red respectively, to show the direction in which correction is being made.

The electrical circuitry is next considered in greater detail. A suitable form of power supply is shown in FIG. 7. It is energized from an A.C. supply line under control of a switch S4. This leads to a transformer having two primaries with four leads so that they may be connected in parallel, as shown, for use with a 115 volt supply, and in series for use with a 230 volt supply.

A full wave rectifier circuit centers about the tube V18, which may be a type 5V4GTB. The secondary provides 1000 volts center tapped for the anodes of this full wave rectifier tube, and the filament is heated at 5 volts. Series inductors and shunt capacitors provide a suitable filter, so marked. The tubes V15, V16, and V17 are voltage regulator tubes. "B" supply is provided at 75, 150, 225, 245, and 400 volts, as indicated on the drawing.

Additional low voltage secondaries with center taps provide a number of independent supplies for filament heating at 6.3 volts, the first, indicated at 130, having its center tap at ground potential; the second, indicated at 132, having its center tap at 225 volts; and the third, indicated at 134, having its center tap at 150 volts. Supply 130 is used for the filaments of later-described tubes V1, V1-1, V2, V3, V3-1, V4, V6, V8, and V19. Supply 132 is used for the filaments of tubes V5, V5-1, V12 and V13. Supply 134 is used for the filaments of tubes V9, V10, V11, and V14.

To energize the light source lamps, a high density selenium rectifier is provided at 136, this being supplied from a secondary with a tap switch at S5. The circuit is intended to deliver a filtered D.C. to the remote light source lamps, with a potential of 11 volts at the lamps, regardless of voltage drop in the long lines leading from the power supply to the lamps. The tap switch S5 is provided to compensate for any such voltage drop in different installations, and to provide the desired voltage at the lamps.

The two web scanners are alike and have the same wiring diagram. This wiring diagram is shown in FIG. 8 of the drawing. The light source lamp is indicated at I-100 and may be a type #1327. The photoelectric cell is indicated at V100 and may be a type 929 photocell. A pulse developed by the photocell is applied to an amplifying tube V101. This is a dual tube with one grid connected to one side of the photocell, and the other connected to the other. The tube anodes are connected to a single pole, double throw switch S100, which is used to select whichever anode provides a negative-going pulse. The remaining circuitry presupposes that the scanner pulse at switch S100 is negative-going. In practise the printing on the web at the desired point may be black on white, or white on black, so that the resulting pulse may be either positive-going or negative-going, and the switch S100 is appropriately set to provide a negative-going pulse.

This pulse is fed to the grid of one half of an amplifier tube V102, the output of which is an amplified pulse which is now positive-going. This is fed to the grid of the other half of tube V102, which is connected to a cathode resistor and acts as a cathode follower. The said cathode resistor is not shown in FIG. 8 because it is located in the computer shown in FIG. 10. The purpose of the cathode follower is to provide a low impedance output, matching a low impedance line extending all the way from the scanner to the computer, and to make it feasible to use an ordinary or non-shielded line for delivery of the web scanner pulse, indicated at 136. The other connections shown on terminal strip 138 are for ground and for filament and "B" voltages. Tube V101 may be a type 5814WA, and tube V102 may be a type

6201, their heater filaments being shown at 137. The conductors leading from terminal strip 138 terminate at their far end in a multiple prong connector for connection to a receptacle in the computer circuitry.

The circuit for the phase micrometer is shown in FIG. 9. The light source lamp I-100 corresponds to that shown at 100 in FIG. 5, and may be a type 1327. It serves two optical systems, one of which terminates in photoelectric cell V200, and the other in photoelectric cell V201, these being type 922. The output of cell V200 is the sloping or micrometer gate (shown at 124 in FIG. 6), and is applied to the grid of one half of the tube V202, which may be a type 5814WA. This is connected and used as a cathode follower. The output of cell V201 is the live gate (shown at 118 in FIG. 6), and is connected to the grid of the other half of tube V202, which is also connected and used as a cathode follower.

Inasmuch as the normally fixed parts of the entire phase micrometer head are rotatably adjustably adjustable, to establish any desired phase relation to the print cylinder, the connections preferably are made through slip rings which are schematically indicated in superposed relation at 149. These lead to a terminal strip 142, and conductors from this extend all the way to the computer where they terminate in a multiple prong detachable connector for connection to a receptacle in the computer circuitry.

The purpose of the different conductors is clear from the drawing, the upper conductor providing a low voltage supply for the light source lamp and the heater filament shown at 144 for the cathode follower tube V202. There are conductors for the 225 volt and 75 volt "B" supplies for the tube and for the photocells respectively, and for a ground connection, as well as a conductor for the live gate and another for the micrometer signal.

It may be mentioned that in the particular circuitry here shown the live gate has a base line at 62 volts and goes up to 78 volts, and the micrometer signal has a base line at 72 volts and goes up to 80 volts or more.

The circuitry of the computer is shown in FIG. 10 of the drawing. The bundle of conductors from the phase micrometer terminates in a plug received in a receptacle 170, shown at the bottom left. The live gate is indicated at 172, and is supplied to the cathodes of the righthand half of the tubes V1B and V1-1 (the B half). In these tubes the live gate combines with the desired pulse from each of the two scanners. The bundle of wires from the scanners terminates in a plug received in a scanner receptacle 174, shown at the upper left. The pulse from one scanner is supplied to the grid of tube V1A, and the pulse from the other scanner is supplied to the similar left grid of tube V1-1.

The micrometer signal leaves receptacle 170 on conductor 176, and is regulated to desired shape and dimension, and is divided to provide two like and isolated outputs in the group of tubes V2, V3A, V4B, and V3-1A, the latter two being used as cathode followers which provide the desired dual output indicated at 178 and 180.

The computer selects the desired pulse as follows. Pulses coming from one web scanner are capacitively coupled to the grid of tube V1A (one half of a type 6SL7 tube). The resistor of the cathode follower tube in the scanner (the right half of tube V102 in FIG. 8) is shown at R1. This stage is normally cut off by a +2.5 or +4.0 volt bias, depending upon the position of switch S1. Positive pulses on the grid cause plate current to flow through resistor R8, dropping the plate voltage. This drops the grid of tube V1B below +75 volts.

The cathode of tube V1B receives the live gate signal, its voltage changing between +62 volts when the live gate is "closed" to +75 volts when the live gate is "open." If a grid pulse occurs while the live gate is "closed", or if the live gate is "open" without a simultaneous grid pulse, the plate current of tube V1B is reduced but not to cut off, the flow of current producing a voltage drop

across resistor R10. However, if a grid pulse occurs while the gate is "open", the plate current of tube V1B is cut off, causing the plate to rise to +245 volts. This rise becomes the "selected web pulse," shown at 175 and 177, which is fed to the pick-off pulse generator tube V5 and to the control grids of "lengthen" and "shorten" relay control tubes V12 and V13. Tubes V5, V5-1, V12 and V13 are thyratron tubes, type 2050.

All of this circuitry is duplicated for the other scanner, using cathode follower resistor R1-1 and tube V1-1, leading to thyratron V5-1. The sensitivity (bias) switch S1 controls both scanner pulses.

The "selected web pulse" from tube V1 triggers tube V5 (or from tube V1-1 triggers tube V5-1), the triggered tube acting as the pickoff pulse generator. The pickoff pulse is a sharp pulse located coincident with the leading edge of the selected web pulse (the latter being suggested at 175 and 177). The tubes V5 and V5-1 are thyatrons, and are normally cut off by the negative bias present on both grids. During this time the capacitor C20 charges up to the +400 volts supply voltage. When the selected web pulse turns on the plate current, the capacitor C20 discharges through tube V5, producing a current pulse of high amplitude and very short duration through the primary of the transformer T2. This causes voltage pulses a few microseconds long to appear across the transformer secondaries.

The secondary windings are connected in series with a neon glow lamp I4 (type NE51 in this instance), and across a diode switch circuit consisting of four silicon diodes (type IN459) in bridge formation indicated at SR. When the voltage reaches the ionization potential of neon lamp I4 a current pulse a few microseconds long flows through the diodes. The lamp I4 acts as a high frequency switch which breaks down for the selected pulse. This effectively closes the circuit between the micrometer signal and the capacitor C21, causing the capacitor to charge up to the voltage which the regulated micrometer signal has reached at the instant of the pickoff pulse. The capacitor charges only to the voltage existing at the instant of the pulse on the sloping side of the micrometer signal. This description applies also to the lower circuit following tube V5-1 for other scanner pulse.

After the pickoff pulse, the capacitor C21 is disconnected from the micrometer signal, and its voltage remains at the picked off value until the next pulse. Capacitor C21 is connected to the grid of a cathode follower tube V3B (or V3-1B for the similar lower circuit). The cathode current flows through R56 and R57 to ground. Tube V3 is a type 5691. The resistors R56 and R57 are proportioned (in this case 2K and 100K ohms) so that the junction will be at +75 volts when the grid is at +75 volts. The voltage at this junction becomes the "proportional control voltage" for the deviation circuits, that is, circuits which respond to deviation.

The capacitor voltage will slowly return to +75 volts as the capacitor discharges through the resistor R55 (which here has a value of 100M). This resistor is used to return the proportional control voltage to the +75 volt reference value when the press is stopped.

The micrometer regulator automatically controls the waveform and peak voltage of the micrometer signal at the left center junction of silicon diode bridge SR. The micrometer signal input at receptacle 170, coming from the phase micrometer, is fed through a one megohm resistor R38 to the grid of the cathode followers V2A (a type 6SL7 tube) and V4B (a type 5691WA tube). The cathode resistor of tube V2A is a voltage divider leading to tube V4A. The tube V4A is connected grid to anode to act as a diode, and is connected between the junction of the voltage divider beneath tube V2A and a capacitor C19, the latter being in parallel with a resistor R41. The diode charges the capacitor when the micrometer signal exceeds +80 volts. The capacitor voltage represents the maximum voltage of the

micrometer signal, and is fed to the grid of a cathode follower V2B, causing its cathode to follow. The cathode resistor of V2B also is a voltage divider. The junction voltage controls the grid of a tube V3A (a type 5691 tube) whose plate is connected to the resistor R38 by a conductor 182. Therefore, the micrometer signal is regulated or stabilized because any drop in the generated micrometer signal is counteracted by a decrease in the plate current of tube V3A.

Coming back now to the utilization of the pickoff "proportional control voltage," that from cathode follower V3B is connected to one grid of tube V8, a type 6SL7G tube operating as a difference amplifier. Similarly that from the cathode follower V3-1B is connected to the other grid of tube V8 for the other pickoff. Consequently deviation from correct repeat length is manifested as an unbalanced output. The output is taken from the two plates of tube V8 in push-pull, one plate voltage rising when the other falls. With perfect repeat length, there is balanced output from the difference amplifier V8.

The outputs are directly coupled to the grids of tubes V9A and V9B, a type 6SL7B tube operating as a dual cathode follower. The cathode current of tube V9A flows through a voltage divider connected from the cathode to ground, and the output is taken from the junction of its divider.

The voltage between these dividers, that is, the relative voltage, is a measure of the instantaneous repeat-length deviation. With the signal selector switch S-6 in the left position shown, the output to receptacle 184 gives this voltage as an instantaneous voltage. The receptacle 184 leads to meter 31 (corresponding to that shown in FIG. 5), and therefore indicates the instantaneous deviation. The output of V9 is also connected through a dual smoothing network consisting of R66 and C22, and R71 and C23, to the grids of another dual cathode follower, V10A and V10B (a type 6SL7G tube). The output of this tube is also taken from cathode voltage dividers; one output from one junction; and the other from the other junction. The voltage between these two junctions is a measure of an average deviation, which may be fed to receptacle 184 and thence to indicator recorder 31 when switch S6 is in the middle position.

The tube V9 (A and B) provides the instantaneous deviation signal. The tube V10 (A and B) in conjunction with the integrating resistance-capacitance networks connected to their grids, provides the average deviation signal.

If automatic correction is provided, additional circuits leading to relays are used. The averaged directional control voltage from tubes V10A and V10B is fed by conductors 186 and 188 into a 6SL7 type dual triode marked V11. With no repeat length deviation, both sections of the tube are conducting, and both plates are at +185 volts. With repeat-length deviation one grid goes negative and the other positive. When a grid goes sufficiently negative the plate current of that section is cut off and the plate voltage rises to +225 volts. The amount that the grid goes negative before it cuts off the plate current depends upon the setting of a control potentiometer C1. This potentiometer sets the cathode voltage on tube V11, and thus establishes the tolerance or minimum deviation above which a correction takes place.

When the left side of tube V11 is cut off, its plate voltage rises to +225 volts and this voltage is fed to a control grid of a type 2050 thyratron marked V12, putting this grid at its cathode voltage. However, the thyratron is still cut off by the negative bias on its other control grid. If, however, the selected web pulse is applied simultaneously to the other control grid, the thyratron conducts and remains conducting until its plate circuit is opened. When this thyratron conducts, the "lengthen" relay 190 is energized, its contacts in the correction system are closed, a green correction lamp 11 is lit on the computer panel, and a duplicate green lamp is lit at the correction unit or wherever desired. If the apparatus is being used for

automatic operation the correction motor is energized for a "lengthen" correction, the connection being made through receptacle 184.

A suppressor network consisting of R22 and C14 may be connected across the relay contacts to prevent arcing. A buffer condenser may be used to prevent transient voltage surges from getting into the power supply.

Similar operation takes place when the plate current of the right half of tube V11 is cut off, except that the thyratron tube V13 conducts; the "shorten" relay 192 is energized; the red correction lamp 12 is lit on the correction computer and at the correction station; and the correction motor is energized for a "shorten" correction.

The thyratron V12 or V13, once conducting, remains conducting, and must be cut off, which is done by a correction timing circuit. The length of correction is determined by the instantaneous deviation, while the direction or sense of the correction is determined by the average deviation.

The correction timer input voltages from the instantaneous deviation circuit are fed through conductors 196, 198 into an RC timing network consisting of resistors R24, R25, and capacitors C17, and C18. Capacitors C17 and C18 charge up to these input voltages. Both the "lengthen" and "shorten" relays 190 and 192 energize a set of additional relay contacts in the proportional timing circuit, these relay contacts being shown at 190' and 192'.

As previously described, it is the control potentiometer voltage which goes negative from 150 volts which controls the direction of the correction. When either the "lengthen" or "shorten" relay is energized its corresponding timing capacitor C17 or C18 is charged negatively with respect to 150 volts, and this voltage is placed on the left grid of a tube V14 (a type 6SL7) tube. This grid voltage then rises linearly as the capacitor, either C17 or C18, starts to charge up to +225 volts. This controls the right half of the tube V14 which controls the coil of a timing relay 194. (Its contacts 194' are shown at the right of relay 192.)

As the grid voltage rises it reaches a point where the tube V14 conducts and the timing relay 194 is energized, and its contacts 194' are pulled in. The voltage at which the tube conducts depends upon the setting of control potentiometer C1, previously mentioned. The time interval determined by the linear rise in grid voltage is proportional to the instantaneous deviation.

The timing relay 194 opens the plate circuit of the thyratron, de-energizing the control relays (either 190 or 192 as the case may be). This also resets the averaging circuit at the tubes V9 and V10, through the closing of contacts 194" of relay 194 (shown near tube V10A). The de-energized control relay (190 or 192) in turn resets the timing circuit. Of course the correction at the correction motor stops.

The rotary variable resistor 200 is used to compensate for different sizes (diameters) of printing cylinder. The said resistor is connected in series with the indicator recorder 31. The germanium diode bridges 33 in FIG. 10, shunting the meters M, are used to protect the meters from surge currents.

The parts shown at 202 in the scanner pulse supply lines are transistors used as diodes to eliminate all negative-going pulses. The rectifiers shown at 204 are silicon diodes, type IN459 which are used as a clipper which cuts off the positive going pulse above the bias, that is, the tube responds to the pulse but does not feel the shock of a high voltage. The silicon diode 205 is used to clip the live gate signal at the desired voltage, in this case 75 volts.

The three position switch S6 makes it possible to operate the indicator-recorder 31 in response to either instantaneous deviation or average deviation from correct repeat-length. The correction circuitry centering around tubes V12, V13 and V14, for control of a correction motor, responds to both instantaneous and average deviation,

in that the direction or sense of the correction depends upon the average deviation, but the amount of the correction depends on the magnitude of the instantaneous deviation as the correction is being made.

There is a third position of switch S-6, this being the position furthest to the right in FIG. 10. It is used to show on the indicator-recorder the adjustment of the potentiometer C1, or in other words, to show the tolerance position to which the correction circuit is set. It shows that value of deviation above which the correction circuit will function or come into operation to cause a correction.

The short lines 210 and 212 for the scanner pulses are shielded inside the computer, as shown at the upper left in FIG. 10, but this precaution is not needed for the long external lines from the scanners.

The combination of the sharp pick-off pulse triggered by the selected web scanner pulse with the micrometer signal is shown at 179 and 181 in FIG. 10. The loading effect of current flowing in capacitor C21 at the instant of pick-off pulse is shown by the break in the waveform of the sloping edge. At the same conductors, the micrometer signal is shown at 178 and 180 in the absence of a pick-off pulse as when the system is not properly phased.

It is important throughout the circuitry shown to provide for isolation of each stage from other stages. An undesired relation may be established through a common B-plus supply, or a common tube. For example, in FIG. 10 the cathode followers V4B and V3-1A serve to isolate one micrometer signal from the other. Also the bridge SR in combination with the neon lamp 14 serve to eliminate all voltages except the voltage at the instant of the pick-off pulse. To make that voltage useful it is used to charge a capacitor, and thus the voltage on the capacitor becomes an indication of repeat length, as described in connection with lines 126 and 128 in FIG. 6.

There is an important advantage in using a micrometer signal with a sloping waveform, combined with a pick-off pulse or pip which shifts in location along the slope, to determine a voltage relative to a reference voltage, in lieu for example of a measurement of the time interval between two scanner pulses. In the latter case difficulty would arise in the event of a change of rotative speed of the print cylinder or press being used. This is so because a time difference would not be in linear relation to a physical change in repeat length. The same time difference would represent a larger error in repeat length, when a press is running faster. However, with the present circuitry there is automatic compensation, because the slope of the micrometer signal is itself produced by the rotation of the phase micrometer (96 in FIG. 5) and changes automatically with a change in speed. At higher speed the slope is steeper with respect to time (though unchanged with respect to the rotating cylinder). Referring to FIG. 6, with a steeper slope the same voltage difference between lines 126 and 128 is produced by a smaller time difference between pulses. Because of this the present circuitry performs correctly independently of the speed of operation of the equipment.

It will be understood that although specific tube types and components and specific voltage values, etc. have been given in the foregoing description, these have been set forth for convenience and by way of example, and are not to be considered in limitation of the invention.

It is believed that the construction and operation of our apparatus for length measurement and control in web printing, as well as the advantages thereof, will be apparent from the foregoing detailed description. The scanners may be rigidly and fixedly mounted in compact or close spacing, and yet the effective distance therebetween, that is along the web, may be readily and accurately and widely varied, in this case over a ratio of two and one-half to one. The measurement of deviation from correct repeat length may be used to indicate the deviation, or to record the deviation, or to correct the devia-

tion, in any desired combination, or all three as here shown.

It will be apparent that while we have shown and described our invention in a preferred form, changes may be made, without departing from the scope of the invention, as sought to be defined in the following claims.

We claim:

1. Apparatus for repeat length measurement in web printing by means of a print cylinder, said apparatus comprising a first optical photoelectric scanner for scanning a marker on a moving web to produce an electrical pulse, a second scanner for scanning the same marker at the correct distance of one or more repeat lengths from the first scanner to produce a second electrical pulse, means geared to said print cylinder for producing a micrometer signal having a sloping portion at the location of the marker, electronic circuitry for combining the pulses with the micrometer signal, and means utilizing the relative displacement of the pulses along the sloping portion of the micrometer signal, as a measure of deviation from correct repeat length.

2. Apparatus for repeat length measurement in web printing by means of a print cylinder, said apparatus comprising a first optical photoelectrical scanner for scanning a marker on a moving web to produce an electrical pulse, a second scanner for scanning the same marker at the correct distance of one or more repeat lengths from the first scanner to produce a second electrical pulse, means geared to said print cylinder for producing a live gate at the approximate location of the marker, additional means geared to said print cylinder for producing a micrometer signal having a sloping portion at the location of the marker, electronic circuitry for so combining the pulses and the live gate as to effectively eliminate all other pulses produced elsewhere along the web, electronic circuitry for combining the resulting selected pulses with the micrometer signal, and electronic circuitry to compare the relative position of said pulses along the sloping portion of the micrometer signal, as a measure of deviation from correct repeat length.

3. Apparatus for repeat length measurement in web printing by means of a print cylinder, said apparatus comprising a first optical photoelectric scanner for scanning a marker on a moving web to produce an electrical pulse, a second scanner for scanning the same marker at the correct distance of one or more repeat lengths from the first scanner to produce a second electrical pulse, means geared to said print cylinder for producing a micrometer signal having a sloping portion at the location of the marker, electronic circuitry for combining the pulses with the micrometer signal, a first capacitor and means to charge the same with a voltage dependent on the location of one pulse along said sloping portion, a second capacitor and means to charge the same with a voltage dependent on the location of the other pulse along said sloping portion, a difference amplifier, means to apply said capacitor voltages to said difference amplifier, and means to utilize the resulting difference signal as a measure of deviation from correct repeat length.

4. Apparatus for repeat length measurement in web printing by means of a print cylinder, said apparatus comprising a first optical photoelectric scanner for scanning a marker on a moving web to produce an electrical pulse, a second scanner for scanning the same marker at the correct distance of one or more repeat lengths from the first scanner to produce a second electrical pulse, means geared to said print cylinder for producing a live gate at the approximate location of the marker, additional means geared to said print cylinder for producing a micrometer signal having a sloping portion at the location of the marker, electronic circuitry for so combining the pulses and the live gate as to effectively eliminate all other pulses produced elsewhere along the web, electronic circuitry for combining the resulting selected pulses with the micrometer signal, a first capacitor and means

to charge the same with a voltage dependent on the location of one pulse along said sloping portion, a second capacitor and means to charge the same with a voltage dependent on the location of the other pulse along said sloping portion, a difference amplifier, means to apply said capacitor voltages to said difference amplifier, and means to utilize the resulting difference signal as a measure of deviation from correct repeat length.

5. Apparatus for repeat length measurement over a wide range of say two to one, in web printing by means of a print cylinder, said apparatus comprising two fixed rolls and a third movable roll which together form a loop of web having parallel sides, a first optical photoelectric web scanner located at one fixed roll for scanning a marker on a moving web to produce an electrical pulse, a second web scanner located at the other fixed roll for scanning the same marker at the correct distance of one or more integral whole repeat lengths from the first scanner to produce a second electrical pulse, means mounting the movable roll for precision adjustment of its position for a long distance along a plane bisecting the space between the sides of the loop and thereby adjusting the length of the web between the scanners, a long scale and a pointer relatively moved by the movable roll and marked in terms of the actual repeat length between the scanners, electronic circuitry to compare the relative time of occurrence of said pulses, and means to utilize a resulting departure from simultaneous occurrence as an indication of deviation from the repeat length indicated by the scale and pointer, whereby the position of the movable roll when changed to obtain simultaneous occurrence of said pulses provides a direct measurement by the scale and pointer of a repeated length marked on the movable web.

30 6. Apparatus for repeat length measurement over a wide range of say two to one, in web printing by means of a print cylinder, said apparatus comprising two fixed rolls and a third movable roll which together form a loop of web having parallel sides, a first optical photoelectric web scanner located at one fixed roll for scanning a marker on a moving web to produce an electrical pulse, a second web scanner located at the other fixed roll for scanning the same marker at the correct distance of one or more integral whole repeat lengths from the first scanner to produce a second electrical pulse, means mounting the movable roll for precision adjustment of its position for a long distance along a plane bisecting the space between the sides of the loop and thereby adjusting the length of the web between the scanners, a long scale and a pointer relatively moved by the movable roll and marked in terms of the actual repeat length between the scanners, the means for adjusting the position of the movable roll comprising spaced screws at the ends of the roll carrying the bearings thereof, and means gearing the screws together for simultaneous equal rotation, electronic circuitry to compare the relative time of occurrence of said pulses, and means to utilize a resulting departure from simultaneous occurrence as an indication of deviation from the repeat length indicated by the scale and pointer, whereby the position of the movable roll when changed to obtain simultaneous occurrence of said pulses provides a direct measurement by the scale and pointer of a repeated length marked on the movable web.

65 7. Apparatus for repeat length measurement in web printing by means of a print cylinder, said apparatus comprising two fixed rolls and a third movable roll which together form a loop of web having parallel sides, a fixed photoelectric optical web scanner located at one fixed roll for scanning a marker on a moving web to produce an electrical pulse, a second web scanner located at the other fixed roll for scanning the same marker at the correct distance of one or more repeat lengths from the first scanner to produce a second electrical pulse, means mounting the movable roll for precision adjustment of

its position along a plane bisecting the space between the sides of the loop and thereby adjusting the length of the web between the scanners, a scale and a pointer relatively moved by the movable roll and marked in terms of the repeat length between the scanners, means geared to said print cylinder for producing a micrometer signal having a sloping portion at the location of the marker, electronic circuitry for combining the pulses with the micrometer signal, and means utilizing the relative displacement of the pulses along the sloping portion of the micrometer signal, as a measure of deviation from correct repeat length.

8. Apparatus for repeat length measurement in web printing by means of a print cylinder, said apparatus comprising two fixed rolls and a third movable roll which together form a loop of web having parallel sides, a fixed photoelectric optical web scanner located at one fixed roll for scanning a marker on a moving web to produce an electrical pulse, a second web scanner located at the other fixed roll for scanning the same marker at the correct distance of one or more repeat lengths from the first scanner to produce a second electrical pulse, means mounting the movable roll for precision adjustment of its position along a plane bisecting the space between the sides of the loop and thereby adjusting the
